(57) **CLAIM**

I claim the ornamental design for an assembled primary end cap for a headrail, as shown and described.

DESCRIPTION

FIG. 1 is an isometric view looking upwardly at a bottom, a first end, and a first side of the assembled primary end cap for a headrail according to a first embodiment of the present invention;

FIG. 2 is an elevation of the first end of the assembled primary end cap, which is identical for both the first embodiment and a second embodiment, shown in FIGS. 8-13, of the present invention;

FIG. 3 is a top plan view of the assembled primary end cap according to the first embodiment;

FIG. 4 is an elevation of the first side of the assembled primary end cap according to the first embodiment;

FIG. 5 is a bottom plan view of the assembled primary end cap according to the first embodiment;

FIG. 6 is an elevation of a second end of the primary end cap according to the first embodiment;

FIG. 7 is an elevation of a second side of the assembled primary end cap according to the first embodiment;

FIG. 8 is an isometric view looking upwardly at a bottom, a first end, and a first side of the assembled primary end cap for a headrail according to a second embodiment of the present invention;

FIG. 9 is a top plan view of the assembled primary end cap according to the second embodiment;

FIG. 10 is an elevation of the first side of the assembled primary end cap according to the second embodiment;

FIG. 11 is an elevation of a second end of the primary end cap according to the second embodiment;

FIG. 12 is a bottom plan view of the assembled primary end cap according to the second embodiment; and,

FIG. 13 is an elevation of a second side of the assembled primary end cap according to the second embodiment.
